Milton A. Dannenberg, Chicago, Ill.

Application June 3, 1954, Serial No. 30,787

Term of patent 14 years

(Cl. D3—13)

To all whom it may concern:

Be it known that I, Milton A. Dannenberg, a citizen of the United States and a resident of Chicago, Illinois, have invented a new, original, and ornamental Design for a Cap, of which the following is a specification, reference being had to the accompanying drawing, forming a part hereof.

Fig. 1 is a front perspective view of a cap embodying my new design, with the ear flaps and neck flap up.

Fig. 2 is a similar view of the same, but with the ear flaps down and the neck flap up.

Fig. 3 is a rear perspective view of the same, but with the ear flaps and the neck flap down.

The essential features of my design reside in the portions shown in solid lines on the drawing.

I claim:

The ornamental design for a cap, substantially as shown and described.
